UNITED STATES PATENT OFFICE.

HARRY M. JACOBS, OF SCHENECTADY, NEW YORK, ASSIGNOR, BY MESNE ASSIGNMENTS,
TO UNION SWITCH AND SIGNAL COMPANY, A CORPORATION OF PENNSYLVANIA.

SLOW-ACTING SECTIONALIZING DEVICE.

1,272,446.

Specification of Letters Patent. Patented July 16, 1918.

Application filed February 17, 1916, Serial No. 8,971. Renewed May 21, 1918. Serial No. 235,857.

To all whom it may concern:

Be it known that I, HARRY M. JACOBS, a citizen of the United States, residing at Schenectady, in the county of Schenectady 5 and State of New York, have invented certain new and useful Improvements in Slow-Acting Sectionalizing Devices, of which the following is a specification.

My invention relates to automatic devices 10 for connecting together the several sections of a sectionalized transmission line. When, after an interruption of service, power is to be reapplied to a transmission line, it may be that the power necessary to start the operation of the entire system is much greater than the ordinary full load power required for the system. For example, in a railway signaling system, in which relays and signals are supplied by a transmission line, the 15 power necessary to clear all signals at once may be three or four times the normal operating power of the system. This is due to the fact that much more power is usually required to clear a signal than to hold the 20 signal at the clear indication. Thus a great increase in the size of the generating apparatus above that required for normal operation is necessary.

In my invention, however, when the line 25 is to be energized, power is first applied to one section only, and after an interval of time sufficient to permit the apparatus associated with that section to assume such condition that it consumes only the normal power, power is applied to another section, and so on. Thus the entire transmission line may be gradually energized in such manner that the starting power is not much greater than the normal load.

I will describe certain forms of apparatus 30 embodying my invention, and will then point out the novel features thereof in claims.

In the accompanying drawings, Figure 1 35 is a diagrammatic view showing a transmission line having applied thereto one form of apparatus embodying my invention. Fig. 2 is a view of one of the circuit controllers P with its operating mechanism O, shown in Fig. 1. Fig. 3 is a view of one 40 of the circuit controllers P with another form of operating mechanism O'. Fig. 4 is a diagrammatic view showing another form of transmission line having applied

thereto another form of apparatus embodying my invention. Fig. 5 is a detailed view of one of the switches P with its operating mechanism O" shown in Fig. 4.

Similar reference characters refer to similar parts in each of the several views.

Referring first to Fig. 1, I have here shown a transmission line comprising two wires 1, 2, which line is divided into sections A, B, etc. The several sections may be connected with and disconnected from each other by circuit controllers P, one such circuit controller being located between each two adjacent sections. Current is supplied to the transmission line by means of a generator 3, here shown as a single phase alternator. Transformers T¹, T², T³, etc., supply power to electrical loads of any description such as signals, lamps, etc.

As here shown, each circuit controller P comprises fixed contacts 15, 16 and 17, 18, 45 which are bridged by bars 19 and 20 respectively when the circuit controller is in the closed position, so as to connect adjacent sections of the transmission line. Referring particularly to Fig. 2, bars 19 and 20 are rigidly attached to, and electrically insulated from a vertically movable switch actuating rod 14 which carries at its lower extremity an armature 21 of an electromagnet 22. Fixed also to this rod is a shoulder 23 adapted to be engaged by a latch 24 pivoted at 150 and controlled by a magnet 25, which latch is adapted to hold the switch P closed after it has been closed and while the electromagnet 25 is energized. Another 50 shoulder 26 on rod 14 is adapted to operate a contact finger 27 of a contact C, to close this contact C when the switch P is closed. Two relays R^A and R^B are provided with contact fingers 31 and 29 respectively, which 55 relays are of a time element type. That is, when the winding of either of these relays is energized, the contact will not operate at once, but only after a predetermined interval of time. There are many ways of 60 procuring this time interval. For the sake of simplicity I have here shown the armatures of relays R^A and R^B in operative connection with dash pots 30^A and 30^B respectively. The time of operation of these dash pots is 65 adjusted in the well known manner by valves 33. Contact 40—60 of relay R^B is 70 prevented from opening until armature 29

almost closed by providing a spring contact finger 60, which is distorted as shown when the relay is deenergized. Relay R^A is energized by the circuit: from transformer 35, 5 through wire 38, contact 60-40 of relay R^B , wire 41, energizing winding 46 of relay R^A , wire 39 to transformer 35. Thus this relay is energized when the back contact of relay R^B is closed and when potential is supplied 10 to an adjacent section of the transmission line, designated in Fig 2 by reference character A. The energizing circuit of relay R^B is as follows: from transformer 35, through wires 38 and 42, contact C, wire 43, 15 energizing winding 45 of relay R^B , wires 44 and 39 to transformer 35. Hence relay R^B is energized when potential is applied to an adjacent section A of the transmission line and contact C is closed, in other words, 20 when the switch P is closed. Magnet 25 is connected directly across transformer 35 by means of wires 47 and 48, hence this magnet is energized whenever there is potential on section A of the transmission line. Magnet 22 is energized by the following circuit: 25 from transformer 35, through wires 38 and 50, contact 51-31 of relay R^A , wire 52, energizing winding 49 of magnet 22, wires 53 and 39 to transformer 35. Therefore magnet 22 is energized when contact 51-31 30 of relay R^A is closed.

I have shown all the apparatus in the positions assumed when there is no current supplied to the transmission system. When 35 voltage is applied to the line by closing switch S, only section A is connected with generator 3, for all circuit controllers P are open. Transformer 35, the primary of which is connected to section A of the transmission line, is then energized, so that current flows through the winding of the electromagnet 25 of the device O located between sections A and B. Relay R^A is energized, its circuit being closed at contact 40-60 of relay R^B . After a time interval determined by the adjustment of valve 33 of dash pot 30^A, contact finger 31 of relay R^A makes contact with point 51, closing thereby the energizing circuit of the electromagnet 45 22, which attracts its armature 21, so that rod 14 is pushed upward and the circuit controller P is closed. Inasmuch as magnet 25 is energized, the latch 24 holds rod 14 in this position. Furthermore, contact C is also closed and relay R^B is therefore energized. This relay attracts its armature 29, and after a time limit imposed by dash pot 30^B, contact 60-40 opens, thus opening at that point the circuit for relay 50 R^A . The opening of relay R^A opens at contact 31-51 the circuit for magnet 22, but the circuit controller P cannot open because it is locked by latch 24. The object in making relay R^B slow-acting is to insure that circuit controller P is fully closed before energy is

taken off from magnet 22; that is, by constructing relay R^B in this manner the parts may be so adjusted that contact 27 closes before controller P completes its movement, yet energy will not be removed from magnet 22 until after such movement has been completed. If relay R^B were quick-acting, contact 27 would have to be adjusted to close exactly at the moment controller P completes its movement, but such delicacy of adjustment is difficult to secure and maintain. Hence, in the case of a circuit controller having little inertia, a slow-acting means for deenergizing the operating magnet is highly desirable. 80

Thus, when potential is applied to one section, the circuit controller P between that section and the adjacent section closes automatically after a predetermined time interval determined by relay R^A , and after the 85 circuit controller has closed relay R^A is deenergized after an interval of time determined by relay R^B . After the circuit controller is closed and relay R^A has opened, the only energy consumed by the controlling apparatus O is the small amount used by magnet 25 and relay R^B .

When potential is taken off the line, or a short circuit at any section causes a drop in the voltage at the sectionalizing switch, magnet 25 releases latch 24. Rod 14 then drops by force of gravity, thereby opening switch P and contact C, thus breaking the energizing circuit of relay R^B . All the apparatus is then in condition to again close the switch 100 automatically when potential is reapplied to the section.

Referring now to Fig. 3, I have here shown circuit controller P with another form of operating mechanism O'. This mechanism comprises, as before, a slow acting relay R^A , a switch operating magnet 22 and a locking magnet 25. I provide furthermore a slow acting switch M which may be of any type. In this figure I have shown it 110 to consist of a lever 103, pivotally mounted at 104, and connected by a spring 106 to a lug 107 on switch rod 14. A spring contact finger 101 is attached to lever 103 to make contact with point 102. A dash pot 115 105 is operatively attached to lever 103, so that when rod 14 is moved upward, spring 106 will tend to turn lever 103 clockwise about pivot 104, but this motion is retarded by means of dash pot 105. As a result, 120 spring contact finger 101 does not break contact with point 102 until a definite time after switch P is closed. A lug 108 is provided to bear on lever 103, so that lever 103 is turned back to its original position when switch P 125 opens. In order to prevent dash pot 105 from interfering with the counter clockwise rotation of lever 103, valve 190 is made of the check valve type. Relay R^A is energized by current flowing in the circuit: from 130

transformer 35 through wire 120, contact 101-102 of switch M, energizing winding 46 of relay R^A , wire 110 to transformer 35. Hence relay R^A is energized when switch M is closed and potential is applied to section A of the transmission line. Magnet 22 may be energized by current in the circuit: from transformer 35, through wires 120 and 109, energizing winding 49 of magnet 22, contact 51-31 of relay R^A , wire 110 to transformer 35. Magnet 25 is as before connected directly across transformer 35 by wires 47 and 48.

To explain the operation of this modification, of the apparatus embodying my invention, assume the transmission line 1-2 of Fig. 1 deenergized. All the circuit controllers P are then open, relays R^A and magnets 25 are deenergized and switches M are closed. When potential is applied to the transmission line by closing switch S only section A is energized as before. Relay R^A of the mechanism between sections A and B is energized, its circuit being closed at contact 101-102 of switch M, and after an interval of time determined by the adjustment of valve 33 of dash pot 30^A, contact 51-31 of relay R^A closes and current flows in the energizing winding 49 of magnet 22. Armature 21 of magnet 22 is therefore attracted and circuit controller P is closed. Potential is thus applied to section B of the transmission line. As before, magnet 25 locks circuit controller P in the closed position. Contact 101-102 of switch M opens after circuit controller P is closed. Thereby relay R^A is deenergized, and opens at contact 51-31 the energizing circuit of magnet 22. Hence, after circuit controller P is closed the only energy consumed by the apparatus is that required for magnet 25. It will be seen that by making contact M slow-acting I insure that circuit controller P shall be fully closed before magnet 22 is deenergized, and that I accomplish this without the necessity for delicate adjustment of the parts. That is, the movement of arm 103 to open contact 101-102 may be started as soon as controller P starts to move, but owing to the slow-acting feature this contact does not open until well after the movement of controller P is completed, hence magnet 22 remains energized until after its work is accomplished.

Referring now to Fig. 4, I have here shown a transmission line comprising wires 1 and 2 and capable of being supplied from either end or both ends by generators 3 and 3' through switches S and S'. The transmission line is divided into sections A, B, Y, Z. I have shown only two full sections, A and Z; and the beginning and end respectively of two other sections B and Y; between sections B and Y, there may be, of course, any number of sections. Each two

adjacent sections may be connected by a circuit controller P, one of which is shown with its operating mechanism O'' in Fig. 5. Since each of these switches must be operable from either adjacent section, each switch is provided with two transformers 35 and 35^A connected respectively to the two adjacent sections.

Referring now to Fig. 5, the operating and controlling mechanism O'' here shown is similar to that shown in Fig. 3 described above, except that a double pole switch N is used instead of single pole switch M. An additional relay R^A similar to relay R^A is also provided. Relay R^A may be energized through the following circuit: from transformer 35, through wires 130, energizing winding of relay R^A , wire 131, contact 101-102 of switch N, wires 132, 135 and 133 to transformer 35. Hence relay R^A is energized when switch N is closed and potential is applied to section A of the transmission line. The energizing circuit of relay R^A is as follows: from transformer 35^A, through wires 113 and 114, energizing winding of relay R^A , wire 115, contact 101^A-102^A of switch N, wires 132, 135 and 112 to transformer 35^A. Hence relay R^A may be energized when switch N is closed and section B of the transmission line is energized. One energizing circuit for magnet 22 is from transformer 35, wire 130, contact 51-31 of relay R^A , wire 136, energizing winding 49 of magnet 22, wires 135 and 133 to transformer 35. Magnet 22 may also be energized by the completion of the circuit: from transformer 35^A, through wire 113, contact 137-138 of relay R^A , wire 136, energizing winding 49 of magnet 22, wires 135 and 112 to transformer 35^A. In short, magnet 22 may be energized by current flowing from sections A or B of the transmission line, if either relay R^A or R^A is energized.

To explain the operation of this modification of the apparatus embodying my invention, assume that the transmission line shown in Fig. 4 is deenergized and circuit controllers P are open. Then, when potential is applied to section A of the transmission line by closing switch S, relay R^A of the mechanism between sections A and B is energized by current from transformer 35, its circuit being closed at contact 101-102 of switch N. After a time interval determined by the adjustment of valve 33 of dash pot 30^A, contact 31-51 closes and current flows in the energizing circuit of magnet 22. Armature 21 is attracted by electromagnet 22 and closes circuit controller P, which is locked in this position by magnet 25 as explained hereinbefore. When circuit controller P closes, section B of the transmission line is energized. As noted before, switch N opens after circuit controller P has closed, and breaks at contact 101-102 the energiz- 130

ing circuit of relay R^A which therefore opens at contact 31—51 the energizing circuit for magnet 22.

If the transmission line had been energized from the opposite end by closing switch S' , transformer 35 A would have been energized and relay R^A would have closed its contact 137—138 after the lapse of time determined by the adjustment of valve 33 of dash pot 30 A of relay R^A . Then magnet 22 would have been energized by current flowing from transformer 35 A , and by attracting its armature 21, it would have closed switch P and potential 15 would be supplied to section A of the transmission line. Then switch N would have opened the energizing circuit of relay R^A at contact 101 A —102 A . Switch P would have been locked in the closed position by 20 magnet 25 after section A had been energized by the closing of switch P.

If the transmission line is deenergized by opening switch S or S' , or if due to some cause or other potential fails at any of the 25 sectionalizing switches, magnets 25 are deenergized and release their armatures 24, allowing switches P to open by force of gravity.

Although I have herein shown and described only certain forms of apparatus embodying my invention, it is understood that various changes and modifications may be made therein within the spirit and scope of the appended claims without departing 35 from the spirit and scope of my invention.

Having thus described my invention, what I claim is:

1. In combination, a circuit controller, an electromagnetic device for the operation 40 thereof, a relay, means for retarding the closure of said relay, a circuit for the electromagnetic device controlled by a front contact of said relay, a second relay, a circuit for the first relay controlled by a back 45 contact of the second relay, means for retarding the opening of said back contact, and means controlled by the electromagnetic device for energizing the second relay when the circuit controller is operated.
2. In combination, a circuit controller, an electromagnetic device for the operation 50 thereof, a relay for controlling said electromagnetic device, means for retarding the operation of said relay, a second relay controlled by the electromagnetic device for 55 controlling the first relay, and means for retarding the operation of the second relay.

3. A circuit controller biased to one position, an electromagnetic device for operating said circuit controller against its bias 60 to another position, a relay for controlling said electromagnetic device, a circuit for energizing said relay, a contact operated by the circuit controller for controlling the energization circuit of said relay and means 65 for preventing the operation of said contact until a definite period of time after the operation of said circuit controller.

4. In combination, a circuit controller, an electromagnetic device for the operation 70 thereof, a relay for controlling said electromagnetic device, means for retarding the operation of said relay, a slow acting switch controlled by the circuit controller for controlling said relay, and means distinct from 75 said electromagnetic device for holding the circuit controller in the operated position.

5. In combination, a circuit controller biased to the open position, an electromagnetic device for moving said controller to 80 its closed position, means for latching said controller in its closed position, and slow-acting means set into operation by the movement of said controller to its closed position for deenergizing said electromagnetic device.

6. In combination, a circuit controller biased to the open position, an electromagnetic device for moving said member to its closed position, a relay adapted when energized to supply energy to said electromagnetic device, means for latching said controller in the closed position, a contact for deenergizing said relay, and slow-acting means set into operation by the movement 95 of said controller to its closed position for opening said contact.

7. A circuit controller biased to the open position, an electromagnetic device for moving said controller to its closed position, 100 means for latching said controller in its closed position, a relay adapted when closed to supply energy to said electromagnetic device, means for retarding the closure of said relay when the latter is energized, and slow-acting means set into operation by the movement 105 of said controller to its closed position for deenergizing said relay.

In testimony whereof I affix my signature in presence of two witnesses.

HARRY M. JACOBS.
